Primary Examiner — Lilyana Bekic(74) *Attorney, Agent, or Firm* — Steven Ivy P.C.(57) **CLAIM**

I claim the ornamental design for a personal inhaling device, as shown and described.

DESCRIPTION

FIG. 1 is a front elevation view of a personal inhaling device showing our new design;

FIG. 2 is a right side elevational view thereof, the left side elevational view is a mirror image of the right side;

FIG. 3 is a top plan view thereof;

FIG. 4 is a front perspective view thereof;

FIG. 5 is a rear elevational view thereof; and,

FIG. 6 is a bottom plan view thereof.

The broken lines in the drawings depict portions of the personal inhaling device that form no part of the claimed design.
